LATHE TAILSTOCK

Carl F. Lindee, Jr., Chicago, Ill., assignor to Portable
Electric Tools, Inc., Chicago, Ill., a corporation of
Illinois

Application August 3, 1953, Serial No. 26,235

Term of patent 14 years

(Cl. D54—6)

To all whom it may concern:

Be it known that I, Carl F. Lindee, Jr., a citizen of the United States, residing at Chicago, in the county of Cook and State of Illinois, have invented a new, original, and ornamental Design for a Lathe Tailstock, of which the following is a specification, reference being made to the accompanying drawings, forming a part hereof.

In the drawings:

Fig. 1 is a front elevational view of a lathe tailstock showing my new design;
Fig. 2 is a right end view thereof;

Fig. 3 is a plan view;
Fig. 4 is a left hand end view with the handle broken away for convenience of illustration; and
Fig. 5 is a rear view thereof.

I claim:

The ornamental design for a lathe tailstock, substantially as shown.
